HOT WATER HEATER

Theodore H. Piser, Newton, Mass.

Application June 2, 1934, Serial No. 728,685

15 Claims. (Cl. 122—19)

The present invention relates to hot water heaters of the type in which a portion of the flue surrounds the boiler or water tank and its object is to improve and simplify the same and increase 5 the efficiency thereof in the manner hereinafter pointed out.

In water heaters of this type, difficulty has heretofore been experienced in maintaining the boiler substantially concentric with the inner 10 wall of the flue liner, and a portion of the flue, that is to say, the space between the boiler and flue liner, of constant width throughout the length thereof. The boiler when filled with water having considerable weight, it has been 15 found in practice that there is quite frequently a slippage between said boiler and its support which results in reducing the width of that portion of the flue comprised by the space between the boiler and flue liner in one direction and increasing it in the other. As the flue liner is but slightly larger in diameter than the boiler, it will be clear that even a slight relative movement between the two will have a material effect on the separation of these two elements, and this results in greatly diminishing the efficiency of the 20 heater. Then again, boilers for heaters of given size frequently vary slightly in diameter so that difficulty has been experienced in maintaining the same on the laterally-extending supports of 25 fixed dimensions which heretofore have been employed.

My invention contemplates the use of three circumferentially spaced elements such as channel irons having inwardly tapered brackets secured to their upper ends to form a seat for the bottom of the boiler, and which, by virtue of the taper will accommodate boilers slightly varying in diameter. The upper end of the boiler is maintained concentric with the flue liner by the 30 cold water inlet and hot water outlet pipes which pass through a relatively heavy top cover for the flue liner, and also through the top of the boiler to which they are firmly attached.

My invention contemplates also a closure for 35 the lower end of the flue liner as distinguished from the usual practice in which said flue liner is open at its lower end, and a packing of heat insulation material between the bottom closure of the flue liner and the bottom closure of the outside casing, and also between the top cover of said 40 flue liner and the top cover of said casing.

Another feature of my invention comprises 45 means for regulating the effective size of the air intake with the amount of gas supplied to the 50 burners.

Various other features of my invention will hereinafter more particularly be described and set forth in the appended claims.

The drawings which accompany and form a 5 part of this specification illustrate one embodiment of my invention which has given good results in practice.

In the drawings,—

Figure 1 is a central vertical section of a hot 10 water heater embodying my invention;

Fig. 2 is a fragmentary elevation;

Fig. 3 is a transverse section taken on the line 3—3 of Fig. 1;

Figs. 4 and 5 are perspective views of details of 15 the construction;

Fig. 6 is a vertical section taken on the line 6—6 of Fig. 2.

In the illustrative embodiment of my invention, 20 10 is an outer casing enclosing a cylinder of relatively thin metal 11, commonly known as a flue liner, a portion of the flue being the space 12 between said liner and the water tank or boiler 13 which is enclosed within said flue liner concentrically therewith, and spaced away therefrom.

In order to maintain the boiler concentric 25 with the flue liner and prevent all possibility of relative movement therewith, and also to increase the stability of the construction, I employ three channel irons spaced circumferentially 30 around the flue liner to support the same, as well as the entire structure, and also to support and center the boiler with respect to the flue liner.

The channels 14 are arranged on the outside 35 of the lower portion of the flue liner with their flanges 15 abutting the same, and a casting 16 is placed on the inside of the flue liner directly opposite each channel with its outer face near the upper end thereof and in contact with said liner. Bolts 17, 17, or other suitable means, are employed to clamp the flue liner between the channel 40 and the castings.

Each casting 16 is provided with an inwardly-bevelled upper end 18, and preferably is provided with an inwardly-extending bracket 19 disposed 45 immediately below the bevel 18 and forming a ledge upon which the bottom of the boiler may rest. By virtue of the bevelled boiler seat, I compensate for variations in the diameter of the boilers which, as aforesaid, frequently differ in 50 diameter, although made for heaters of given size.

The upper end of the boiler is maintained in concentric relation with the fuel liner by the cold-water inlet pipe 20 and hot-water outlet 55 pipe 21.

pipe 21 which pass through the top 22 of the outer casing and the top closure 23 of the flue liner, each of which may be relatively thick compared to the side walls of the flue liner. The inlet and outlet pipes are in threaded engagement with the boiler, as shown, and suitable means such as the washers 24 and set-screws 25 are provided to lock the top of the casing with respect to the pipes. By virtue of the rigidity of the construction just described, all possibility of relative movement between the upper portion of the boiler and the flue liner is eliminated.

In order to conserve heat and render the apparatus more efficient, I provide the flue liner with end closures, 23 already having been described as the upper end closure and 26 being the lower end closure, and rock wool 27, or other suitable heat insulation material is placed between the end closures of the flue liner and the top and bottom of the outer casing, as well as in the circumferential space between the flue liner and casing.

The boiler terminates short of the bottom of the flue liner to form a combustion chamber in which are placed the gas burners 28, 28' and the door 29 which affords access to said combustion chamber is provided with a perforation 30. Each channel 14 extends through the bottom of the outer casing, as indicated at 15' and may have a foot 15" cast thereon.

30 Air of combustion enters the combustion chamber through the pipe or flue 31 which passes through the bottom closure 26 of the flue liner and the bottom closure 32 of the outer casing, the latter resting on flanges 33 secured to the lower portions 15' of the channels.

Suitably supported to the outside of the outer casing is a system of valves and thermostats comprising the gas filter 34 connected by suitable piping to the pilot burner 35 and the burners 28, 28', 40 the flow of gas through such piping being controlled in the first instance by the cock 36. Normally there is a flow of gas through such piping to the low-input burner 28' by way of the lateral pipe 37 which is independent of the cock 38 arranged to control the flow of gas to the supplemental or high-input burner or burners 28 by way of the pipe 39. Throughout the specification and claims I use the terms "low input burner" or "normally-operating burner" to designate 50 a water-heating burner having a gas-burning capacity of not less than 1500 British thermal units per hour, as distinguished from a pilot burner, such as the burner 35, which usually has a burning capacity of about $\frac{3}{4}$ cubic foot per hour, or about 400 British thermal units per hour, and the function of which is not to heat the water in the boiler but merely to light the water-heating burners and/or to control the safety pilot valve. The terms "supplemental burner" or "high input 60 burner" are used herein to designate a burner which operates only under unusual conditions, as hereinafter set forth and preferably has a gas-burning capacity higher than that of the normally-operating burner. The flow of gas to all the burners is regulated by the thermostatically-controlled valve 40, the thermostat element 41 being disposed in the boiler. A safety pilot valve 42 is provided for the pilot burner and shuts off the supply of gas to the pilot burner when the latter is accidentally extinguished.

Suitably connected with the cock 38 for simultaneous actuation therewith is a valve or damper 43 for regulating the effective cross-sectional area of the air intake pipe or flue, the arrangement 70 being such that when said cock is in position to

shut off the supply of gas to the supplemental burner or burners 28, said damper is closed, i. e., is disposed at right angles to the axis of said flue, and when said cock is open and gas is supplied to said burners, said damper is in the position shown and permits the influx of the amount of air of combustion required by all the burners 28 and 28'. It will be noted however that when said cock 38 and its simultaneously-actuated damper are closed, sufficient air enters said duct 10 to support the combustion of gas supplied to the burner 28' through the central aperture 44 in said damper.

The burner 28' under normal conditions will supply sufficient heat to maintain the water in the boiler at the desired temperature but when there is an unusual demand for hot water, or it is desired to heat water quickly, the cock 38 is opened and the burners 28, herein shown as five in number, are supplied with gas. In such case, the additional amount of air necessary to support the augmented combustion is received into the combustion chamber through the now fully-open inlet pipe 31 which may be provided with a preferably removable cap 45 having an opening somewhat smaller in diameter than said pipe.

It will thus be seen that the air of combustion is under the complete control of the user. I have ascertained by test that when the heater is operated on low-gas input, i. e., when the single burner 28' is employed, the efficiency of the heater is higher than when all the burners are used. The use of an apertured damper 43 in conjunction with said removable cap 45 makes it possible to vary the input of the heater without reducing its efficiency. The air-intake pipe 31, the annular space between the boiler and flue liner, and the air outlet pipe 31' constitute a passageway or flue for the air of combustion, sometimes called "secondary air", and the products of combustion. While in the present exemplification of my invention I have shown the flue-regulating means 43 in that portion of the flue comprised by the air-intake pipe, it will be understood that such means may be disposed in any portion of the flue without change of result.

Having thus described an illustrative embodiment of my invention without however limiting the same thereto, what I claim and desire to secure by Letters Patent is:

1. A hot water heater comprising in combination an outer casing, a flue liner disposed therein, and a boiler enclosed within and spaced away from said flue liner, a plurality of channel irons, blocks each having an inwardly-bevelled end and an inwardly-extending bracket, said channel irons and blocks being disposed on opposite sides of said flue liner, means clamping said liner between said channel irons and blocks, said channel irons extending below the bottom of said outer casing and constituting a support for said heater, and said brackets forming a support for said boiler.

2. A hot water heater comprising in combination a flue liner, a boiler enclosed within said flue liner and spaced away from the same, closures for the upper and lower ends of said flue liner, a plurality of pairs of channel irons and blocks clamped pair by pair on opposite sides of the wall of said flue liner, said blocks having inwardly-extending brackets for receiving the bottom of said boiler, and inlet and outlet pipes passing through the top closure of said flue liner and into said boiler.

3. A hot water heater comprising in combina- 75

tion, a boiler, a normally-operating water-heating burner of sufficient gas-burning capacity to maintain the water in the boiler at a relatively high temperature for normal domestic uses, a supplemental burner, both of said burners being constructed and arranged for fuel of the same type, piping for conveying fuel to said normally-operating burner, piping for conveying fuel to said supplemental burner, a valve controlling the supply of fuel to said supplemental burner, the piping to said normally-operating burner being independent of said valve, an air-intake pipe common to both of said burners, and means controlled directly by said valve for regulating the effective cross-sectional area of said intake pipe.

4. A hot water heater comprising in combination, a boiler, a plurality of water-heating burners disposed for heating said boiler, one of said burners being of sufficient gas-burning capacity to maintain the water in the boiler at a relatively high temperature for normal domestic uses, and all of said burners being constructed and arranged for fuel of the same type, an air-intake pipe common to all of said burners, means for controlling the supply of fuel to some but not all of said burners, and other means actuated directly by said means for regulating the effective cross-sectional area of said intake pipe.

5. A hot water heater comprising in combination, a boiler, a normally-operating water-heating burner of sufficient gas-burning capacity to maintain the water in the boiler at a relatively high temperature for normal domestic uses, a supplemental burner, both of said burners being constructed and arranged for fuel of the same type, piping for conveying fuel to said normally-operating burner, piping for conveying fuel to said supplemental burner, a valve controlling the supply of fuel to said supplemental burner, the piping to said normally-operating burner being independent of said valve, an air-intake pipe common to both of said burners, and an apertured damper controlled directly by said valve for regulating the effective cross-sectional area of said intake pipe.

6. A hot water heater comprising in combination, a boiler, a normally-operating water-heating burner of sufficient gas-burning capacity to maintain the water in the boiler at a relatively high temperature for normal domestic uses, a supplemental burner, both of said burners being constructed and arranged for fuel of the same type, piping for conveying fuel to said normally-operating burner, piping for conveying fuel to said supplemental burner, a valve controlling the supply of fuel to said supplemental burner, the piping to said normally-operating burner being independent of said valve, an air-intake pipe common to both of said burners, and a damper controlled directly by said valve for regulating the effective cross-sectional area of said intake pipe.

7. A hot water heater comprising in combination, a boiler, a normally-operating water-heating burner of sufficient gas-burning capacity to maintain the water in the boiler at a relatively high temperature for normal domestic uses, a supplemental burner, both of said burners being constructed and arranged for fuel of the same type, piping for conveying fuel to said normally-operating burner, piping for conveying fuel to said supplemental burner, a valve controlling the supply of fuel to said supplemental burner, the piping to said normally-operating burner being independent of said valve, an air-intake pipe common to both of said burners, an apertured cap associated with said air-intake pipe for constricting the effective area thereof, and means controlled directly by said valve for regulating the effective cross-sectional area of said intake pipe.

ing the effective area thereof, and means controlled directly by said valve for regulating the effective cross-sectional area of said intake pipe.

8. A hot water heater comprising in combination, a boiler, a low-input water-heating burner of sufficient gas-burning capacity to maintain the water in the boiler at a relatively high temperature for normal domestic uses, a high-input burner, both of said burners being constructed and arranged for fuel of the same type, a valve controlling the supply of fuel to said high-input burner only, a flue common to both of said burners, and means controlled directly by said valve for regulating the effective cross-sectional area of said flue.

9. A hot water heater comprising in combination, a boiler, a plurality of water-heating burners disposed for heating said boiler, one of said burners being of sufficient gas-burning capacity to maintain the water in the boiler at a relatively high temperature for normal domestic uses, and all of said burners being constructed and arranged for fuel of the same type, a flue common to all of said burners, means for controlling the supply of fuel to some but not all of said burners, and other means actuated directly by said means for regulating the effective cross-sectional area of said flue.

10. A hot water heater comprising in combination, a boiler, a low-input water-heating burner of sufficient gas-burning capacity to maintain the water in the boiler at a relatively high temperature for normal domestic uses, a high-input burner, both of said burners being constructed and arranged for fuel of the same type, a valve controlling the supply of fuel to said high-input burner only, a flue common to both of said burners, and an apertured damper controlled directly by said valve for regulating the effective cross-sectional area of said flue.

11. A hot water heater comprising in combination, a boiler, a low-input water-heating burner of sufficient gas-burning capacity to maintain the water in the boiler at a relatively high temperature for normal domestic uses, a high-input burner, both of said burners being constructed and arranged for fuel of the same type, a valve controlling the supply of fuel to said high-input burner only, a flue common to both of said burners, and a damper controlled directly by said valve for regulating the effective cross-sectional area of said flue.

12. A hot water heater comprising in combination, a boiler, a low-input water-heating burner of sufficient gas-burning capacity to maintain the water in the boiler at a relatively high temperature for normal domestic uses, a high-input burner, both of said burners being constructed and arranged for fuel of the same type, a valve controlling the supply of fuel to said high-input burner only, a flue common to both of said burners, an apertured cap associated with said flue for constricting the effective area thereof, and means controlled directly by said valve for regulating the effective cross-sectional area of said flue.

13. A hot water heater comprising in combination, a boiler, a normally-operating low-input water-heating burner of sufficient gas-burning capacity to maintain the water in the boiler at a relatively high temperature for normal domestic uses, a supplemental high-input burner, both of said burners being constructed and arranged for gas, piping for conveying gas to said normally-operating low-input burner, piping for conveying gas to said supplemental high-input

burner, a manually-actuated valve controlling the supply of gas to said supplemental high-input burner, the piping to said normally-operating low-input burner being independent of 5 said manually-operated valve, a flue common to both of said burners, and means controlled directly by said valve for regulating the influx of air through said flue.

14. A hot water heater comprising in combination, a boiler, a burner for said boiler, a flue for 10 said burner, and a cap having an aperture of smaller diameter than said flue, the cross-sectional area of said aperture being sufficient to permit the influx of the air of combustion required for said burner and said cap being removably associated with said flue.

15. A hot water heater comprising in combina-

tion, a boiler, a normally-operating water-heating burner of sufficient gas-burning capacity to maintain the water in the boiler at a relatively high temperature for normal domestic uses, a supplemental burner, a flue of sufficient cross-sectional area to permit the influx of the air of combustion required for both of said burners, a damper in said flue, said damper having an aperture of smaller diameter than said flue, the cross-sectional area of said aperture being sufficient to permit the influx of the air of combustion required by said normally-operating burner when said damper is closed, a valve controlling the supply of gas to said high-input burner only, and means connecting said damper for actuation by said 15 valve.

THEODORE H. PISER.
